UNITED STATES PATENT OFFICE.

ROBERT JOHN, OF NEW YORK, N. Y.

FILM-PRINTING MACHINE AND METHOD.

Application filed July 14, 1923. Serial No. 651,501.

This invention relates to a film-printing machine and method, in which a master film bearing certain designs or pictures is used for printing on a blank film, which may then be used for reproducing the designs or pictures as, for example, in a moving picture apparatus.

This invention has as an object an apparatus in which a master film bearing certain designs may be used for printing upon a blank film in order to reproduce or duplicate the designs in any desired number.

It has as an object a machine in which the printing may be performed on the blank film and the perforations formed in the latter in the exact relationship in which they appear in the master film, and it has also as an object the provision of means whereby the master film will not be damaged during the perforating process.

A further object of the invention is to provide means for sticking the master and blank films together without the formation of air bubbles during the movement through the apparatus, and also to avoid crimping of the blank film along its edges during the operation.

A further object is to provide effective means for advancing the films while they are stuck together, and to perforate the blank film in exactly the correct positions in relation to the pictures.

A still further object is to provide means for separating the master and blank films and separately drying and rewinding them, together with means for supporting the blank film and also the master film while drying.

Other objects will appear hereinafter.

For the sake of clearness, the apparatus and method will be described in respect to the progress of the films through the apparatus.

The invention in its preferred embodiment is illustrated in the drawings, which form part of this specification, and in said drawings:

Fig. 1 represents a side elevation of the entire machine showing the relation between the various mechanisms;

Fig. 2 represents the means for sticking the films together;

Fig. 3 is a top view of said means;

Fig. 4 is a side elevation of the pressure rollers which constitute the squeegee mechanism positioned immediately after the means for sticking the films together;

Fig. 5 represents a front elevation of the said squeegee mechanism;

Fig. 6 shows the clutch mechanisms on 60 the main shaft in side elevation;

Fig. 7 represents a plan of said main shaft and clutch mechanisms;

Fig. 8 is a side elevation of the film-advancing and perforating mechanism; 65

Fig. 9 is a rear elevation thereof;

Fig. 10 is a front elevation thereof;

Fig. 11 is an enlarged side elevation, partly in section, showing the same mechanism;

Fig. 12 is an enlarged rear section of 70 the same mechanism;

Fig. 13 is a side elevation of the winding reels upon which the master and printed films are wound at the end of the operations;

Fig. 14 is a rear elevation of the winding 75 reels;

Fig. 15 is an enlarged side view of the tank 25 and associated parts;

Fig. 16 is a section on line 16—16 of Fig. 12 looking in the direction of the arrows. 80

In the preferred embodiment of the invention, there is shown a frame which is generally denoted by the numeral 1, upon which frame the machine is mounted. At the right of this frame are two reels designated 2 and 2^a, upon which are respectively mounted the master film and the blank or secondary film upon which the printing is to be performed. The master film is unwound over a roller 3 and passes into a tank 4, which tank contains a suitable dye to be used as a printing medium. The film passes through this dye tank over a roller 5 down over a roller 6 and then up to a roller 7 mounted upon a receptacle 8 which may be provided with a plate 9 hinged to the bottom of the wall by hinges 10 and 11 so that the interior may be inspected if desired. In the center of this receptacle is provided a vertical water pipe 12 which has 90 a restricted nozzle 13 at the top thereof, this nozzle having a rectangular slit or opening through which water may be ejected in a vertical stream of more or less solidity or

volume for the purpose to be herein explained. The water is supplied from a receptacle 14 supplied by a water pipe 15 and the water flows by gravity in constant volume in the said pipe 12.

The film moves into this receptacle by passing downwardly around a roller 16 and under a smooth copper or brass plate 17 which is pivoted in a suitable manner adjacent the roller 16 and lies freely against the film with its end against a roller 18 which is positioned just above and to the left of the nozzle 13. At this point it is joined by the blank film which is supplied 15 in the following manner.

The blank film is unwound from the reel 2 past rollers 19 and 20, over roller 21, under roller 22, and up over a guideway 23 which is covered with a layer of felt 24. 20 The roller 22 is positioned within a tank 25 adapted to contain a liquid such as water in order to moisten the film. The excess liquid is wiped off on the felt surface 24 and the film then moves around a roller 26, down 25 around a roller 27, and then against the roller 18, where it meets the master film.

Just at this juncture, and while coming into contact, the two films are washed by the ascending column of water from the nozzle 30 13 in such a manner as to provide a medium of water in the presence of the films as they meet each other, thereby preventing access of air and insuring the secure sticking together of the two films. The water also 35 functions to remove a portion of the dye from the master film so that an excess of dye will be avoided, but the time of contact with the water is not sufficient to remove the dye which is desired for printing on the 40 blank film.

The films now move upwardly to the squeegee rollers shown in Fig. 4, where they are squeezed together by successive rollers and then passed upwardly to the top of the 45 platform of the machine. The squeegee rollers comprise three horizontal pairs of rollers designated 28, 29, 30, 31, 32, and 33. The rollers 28, 30, and 32 are mounted upon a stationary framework attached to the main 50 frame of the machine, and they are driven from the vertical horizontal shaft 34, having at the upper end a gear 35 meshing with a gear 36 on a vertical shaft 37, which has a gear 38 meshing with a driving worm 39 55 mounted upon a driving shaft 40. The rollers 29, 31, and 33 are mounted upon a movable frame 41 which may be moved towards or away from the opposite framework holding the rollers 28, 30, and 32, by 60 means of a worm 42 operated by the hand wheel 43, the frame 41 being supported during its motion by rods 44, four of which are shown in the drawings (Fig. 5). The rollers 29, 31, and 33 are driven from the 65 shaft 40 by means of a shaft 45 having a

pinion 46 meshing with a worm 47 keyed to the shaft 40 for sliding engagement therewith. Shaft 45 has suitable gears 48 meshing with gears 49 on the respective rollers. The shaft 40 is driven from a main shaft 70 50 driven by a motor 51, which is connected thereto by suitable reduction gearing represented generally by 52. A positive clutch mechanism 53 operated by a lever 54 connects the shafts 40 and 50. Other clutch mechanisms are mounted on the main shaft 50 for the purposes to be explained later.

After leaving the rollers, the films move upwardly over a roller 55 and thence outwardly over rollers 56 and 57 to form a loop 58, which may be suspended on a frame or wall at a considerable distance from the machine. The film is returned over the rollers 59, 60, and 61 to a bed or guideway 62, along which films move towards a perforating film-advancing machine denoted generally by the numeral 63.

This machine is driven from the main shaft by means of another shaft 64 connected thereto by a friction clutch 65 operated by a lever 66, a gear 67 being mounted to drive the vertical shaft 68 which is provided with a pinion 69 meshing with a pinion 70, on a shaft 71 having thereon a hand reel 72 for manual operation. An eccentric 73 is mounted on the shaft 71 and reciprocates the film perforating mechanism which is suspended from the rectangular framework 74 having a rectangular opening 75 serving as a bearing for the eccentric block 76. From the rectangular member 74 are suspended the reciprocating rods 77 and 78 to which are attached the punchers 79 and 80 which serve to punch the perforations in the films. A framework 81 is provided having bores therein through which the rods or pistons move. There is also a bore for a reciprocating rod 84 having a hook 83 adapted to be engaged by a slotted plate 82, to catch and pull upwardly the reciprocating rod 84, which is attached to a holding block 85 through which the perforators move, this holding block being intended to hold the films down to the base 62 while the perforating takes place. A spring 86, positioned between the frame 81 and the block 85, tends to depress the latter downwardly against the films. The action of this mechanism therefore is that, with the parts in the position shown in Figs. 11, 12 and 15 with the hook 83 in the bottom of the slot in the slotted plate 82, as the eccentric 73 moves downwardly due to the rotation of the shaft 71, the framework 74 carrying the reciprocating rods 77 and 78 and the slotted plate 82 moves downwardly. Under the action of the spring 86 the rod 84 and block 85 move downwardly until the block contacts with the bed 62, or the films upon the bed, and continues to exert pres-

sure against the bed 62 or the films to hold the films in place, while the eccentric 73 and framework 74 continue to move downwardly forcing the punchers 79 and 80 through the film and through the openings in the bed 62. On the upward movement of the eccentric 73 the framework 74 moves upwardly carrying with it the reciprocating rods 77 and 78 and the plate 82. The block 85 and rod 84 remain motionless however, with the block 85 pressing against the films or bed plate beneath it, until the punchers 79 and 80 are well above the bed 62 at which time the bottom of the slot in the plate 82 contacts with the hook 83 and raises the block 85 so that the films can move forwardly along the bed plate 62. The forwarding means consists of two feed pawls, shown at 87, which are shaped to fit within the perforations in the master film and push it along to the left as viewed in Fig. 11. These pawls are attached to a reciprocating block 88 operated through link 89 from an eccentric 90 which is driven by a gear 91 operated from the shaft 68 by means of a gear 92. A roller 93, mounted on the framework 81, is in engagement with a cam surface 94 upwardly curved at the right, as viewed in Fig. 11, so as to exert a depressing action upon said surface when it is moved to the rear. Adjusting means 95 is provided for adjusting the position of the cam surface 94 with respect to the roller 93.

When the perforating operation has been completed, the films pass on over rollers 96 and 97, forming a loop as at 98, and are then pulled over a support 99, which is preferably curved in the shape of a portion of a cylinder to avoid crimping of the films along the edges and thence down into a drying chamber in which a number of rollers are mounted so that the films may traverse an up and down course for some distance in order to be separated and eventually dried and rewound. The drying chamber is represented by 100 and contains a number of rollers represented by 101 and 102 over which the films pass. Between these rollers are a series of stationary ribbons represented by 103, each ribbon being mounted at a quarter-turn and reinforced by whale-bone ribs 104 which maintain the ribbons in a flat extended condition. The films pass along the surfaces of these ribbons and are maintained in a flat condition thereby. At the roller 105 the films are separated, the master film passing downwardly around the roller 106, upwardly again around the roller 107, and then down around the roller 108, over to the rewinding reel 109; while the printed film passes up over the rollers 110 and 111 and then down to the roller 112 from which it is passed over the succession of rollers and ribbons shown until it is thoroughly dried and arrives at the last roller 113, from which it passes to the reel 114 to be wound in a flat condition. The drying chamber may be supplied with a current of air from a blower 115. A fabric belt 116 is mounted to assist in the carrying of the films, this fabric belt meeting the incoming joined films at a roller 117 and traversing the course with them until they are separated at the roller 105, from which point the fabric belt travels with the printed film around the rollers 111, 112 through the rest of the drying chamber, and is separated from the printed film at a roller 118 whence it passes around several small rollers, as shown, back over to the roller 117.

The mounting of the rewinding reels is shown in Figs. 13 and 14. Reels 109 and 114 are rotated by pinions 119, 120, respectively, these pinions being mounted on a vertical shaft 121 driven by a pinion 122 meshing with another pinion 123 which is driven from the main shaft by suitable means. The reels may be of any suitable construction such as friction held discs 90 spring-pressed by springs 124.

In the operation of the machine, the master film and the blank film are unwound from the reels 2 and 2^a respectively, the master film passing through the dye tank, while the blank film passes through the water tank 25, whereupon they enter the washing box over the rollers 7 and 26 respectively. In the washing box the column of water from the nozzle 13 shuts off the air while the films come into contact and thereafter the film of water between them prevents the entry of air during the subsequent operations. The films are each run over a lower roller in the washing box to give a down-bend to them before coming up to the squeegee rollers. The films are mounted exactly one over the other so that when they come to the squeegee rollers they are perfectly true within limits of accuracy of the cutting of the film. To facilitate this, one edge of all the guide rollers is accurately in line with the film edges. The squeegee rollers above the washing box force the films together and thereafter they move upwardly to the right, as shown in Fig. 1, to provide a long loop 58 in order to provide slack. The joined films are advanced by the pawls 87 step by step, these pawls fitting within the perforations in the master film, which perforations are made larger than in the case of ordinary films. The perforating mechanism for the blank film that underlies the master film, is adjusted with respect to the pawls so that the perforations will come entirely inside of the perforations in the master film, thereby avoiding damage to the latter. The position of the perforations in the blank film with respect to the pictures thereon is thus made to be the same as in the master film. The

pawl operating mechanism is operated by a friction clutch in order to accelerate slowly as otherwise the films would be in danger of being torn by the feed pawls. During the forward movement of the films, the clutches may be manipulated to disengage any one of the mechanisms in order to compensate for undue advance or retardation of the films due to stretching, shrinking or some other cause. The loops 58 and 98 are provided for the purpose of any variations which might take place before such adjustments are made, thus making it unnecessary to keep too close a watch on the machine. After passing the perforating mechanism, the films are passed into the drying chamber 100 and are separated at the roller 105, each film being separately rewound on the reels 109 and 114.

As many widely different embodiments of this invention may be made without departing from the spirit thereof, I do not intend to limit myself to the preferred embodiment shown except as indicated in the following patent claims.

25 I claim:

1. A machine for printing films comprising the combination of reels for holding a master film and a blank film, a dye tank, means to pass the master film through it, 30 means to unite the films by surface contact and exclude air therebetween, squeegee rollers to press the films together, means for extending the films to provide slack, a reciprocating mechanism having pawls which 35 periodically occupy perforations in the master film to advance it, a film-holding block operated to hold the films down when advance has ceased, a reciprocating perforator mounted with relation to the pawls in 40 such a manner as to perforate the printed film through the centers of the perforations in the master film, and means for separating the films and rewinding them.

2. A machine for printing films comprising the combination of reels for holding a master film and a blank film, a dye tank through which the master film is adapted to pass, means to exclude air from between the films, and means to press the films into 50 surface contact to print the blank film from the master film.

3. A machine for printing films comprising the combination of reels for holding a master film and a blank film, a dye tank 55 through which the master film is adapted to pass, means to exclude air from between the films, means to press the films into surface contact to print the blank film from the master film, and means for separating the films 60 after printing.

4. A machine for printing films comprising the combination of reels for holding a master film and a blank film, means for coloring the master film, means to press the films 65 into surface contact to print the blank film

from the master film, means to move the films, a film holding block arranged to clamp the films when movement of the films has ceased, and a reciprocable perforator operable to perforate a film after movement of 70 said holding block has ceased.

5. A machine for printing films comprising the combination of reels for holding a master film and a blank film, means for coloring the master film, means to press the 75 films to surface contact to print the blank film from the master film, means to move the films, a reciprocable perforator operable to perforate a film, and a holding block operable to clamp the films adjacent the points to 80 be perforated during the perforation thereof.

6. In a machine for printing films, a washing box having means for bringing a master film and a blank film into surface contact, and a water supply positioned in proximity 85 to the place of contact to provide a column of water against the contacting films.

7. The invention as claimed in claim 6, with the provision of rollers in the lower part of the washing box around which the 90 films pass and thence proceed upwardly to the place of surface contact.

8. In a machine for printing films, a washing box having means for bringing a master film and a blank film into surface contact, a 95 roller mounted at the top of the box to bring the films into the box, and a water supply positioned in proximity to the place of contact of the films to provide a column of water against the contacting films.

9. In a machine for printing films, a washing box having a vertical water nozzle therein, a roller in close proximity to said nozzle, a movable guide plate resting against the roller, and rollers in the lower part of the 105 box and at the upper edges thereof.

10. In a machine for printing a blank film from a master film, a water nozzle, means for guiding the films into a position to be wet by the water issuing from the nozzle, and 110 means for pressing the films into contact.

11. In a machine for printing a blank film from a master film, a guide for one of the films, a yielding guide for the other film arranged to press the films into contact, and means to direct a jet of adhesive against the 115 contacting surfaces of the films at the point of contact.

12. A machine for printing films comprising the combination of a washing box 120 as claimed in claim 6, and a moistening means for the blank film in advance of said box.

13. In combination with a machine for printing films having a washing box as 125 claimed in claim 6, a moistening means for the blank film in advance of said box and a wiping surface positioned between the box and the moistening means.

14. The invention as claimed in claim 6, 130

in combination with squeegee rollers positioned above the said box.

15. The combination of a washing box as claimed in claim 6, and a dye tank in advance 5 thereof with means for advancing the master film through said tank and into the washing box.

16. In a machine for printing films, means for temporarily sticking the films together, 10 means for providing slack in the jointed films, and an advancing mechanism for the films.

17. The invention as claimed in claim 16, wherein means are provided for stopping the 15 advancing mechanism independently of the machine.

18. In a machine for printing films from a master film, an advancing means for the films comprising pawls which are mounted to reciprocate and periodically enter only the 20 perforations in the master film in order to advance it.

19. In a machine for printing films, the combination of an advancing mechanism, 25 and a perforating mechanism for a film, and a holding mechanism for the films during the perforating operation.

20. In a machine for printing films, wherein in a master film having large perforations 30 is joined to an unperforated film, the combination of an advancing means and a perforating means so adjusted that the perforations are made in the unperforated film through the perforations in the master film 35 without touching the edges thereof.

21. In a machine for printing films, wherein in an unperforated and a perforated film are stuck together, the combination of an advancing means for the films comprising 40 pawls mounted to reciprocate and enter the perforations in the perforated film, a perforating means comprising vertical punchers timed to descend when the pawls have come to rest in a position exactly determined so 45 that the perforations will be made through the centers of the perforations in the perforated film without touching the edges thereof.

22. A method of printing films comprising 50 printing on a blank film from a master film and then perforating the blank with the same relation to the pictures thereon as exists on the master film.

23. The invention as claimed in claim 22, 55 wherein the perforating takes place while the films are stuck together.

24. A method of printing films comprising 60 printing on a blank film from a master film having large perforations along its edges, and then perforating the blank film through the centers of the perforations in the master film without touching the edges thereof, with the same relation to the pictures 65 on the blank as exists on the master film.

25. The invention as claimed in claim 24, wherein the perforation is performed while the films are stuck together.

26. A method of sticking films together to avoid access of air comprising bringing 70 them into surface contact while playing a column of water between them at the point of contact and wherein they come together.

27. A method of printing films comprising 75 coating a master film with a printing material and bringing the master film into continuous surface contact with a blank film while directing a column of water against the continuously advancing films at their point of contact.

28. A method of printing films comprising 80 coating a master film with a printing material, bringing the master film into continuous surface contact with a blank film while directing a column of water against 85 the continuously advancing films at their point of contact, and passing the films between squeegee rollers.

29. A method of printing films comprising 90 coating a master film with a printing material, moistening a blank film and wiping off the excess moisture, advancing both films in continuous surface contact while playing a column of water between them.

30. A method of printing films comprising 95 coating a master film with a printing material, moistening a blank film and wiping off the excess moisture, advancing both films in continuous surface contact while playing a column of water between them, and passing 100 the films between squeegee rollers.

31. A method of printing films comprising 105 applying a printing material to a master film and bringing it into surface contact with a blank film in the presence of a column of water and by squeegee action, perforating the blank film, bringing the joined films into a drying chamber, separating and drying them therein and rewinding them.

32. A machine for printing films comprising 110 the combination of reels for holding a master film and a blank film, a dye tank, means to pass the master film through it, a washing box having means to unite the films by a surface contact and a vertical water nozzle to direct a column of water against the contacting film surfaces, squeegee rollers to press the films together, means for extending the films to provide slack, a reciprocating mechanism having pawls which periodically occupy perforations in the master film to advance it, a film-holding block operated to hold the films down when advance has ceased, a reciprocating perforator mounted with relation to the pawls in such a manner 115 as to perforate the printed films through the centers of the perforations in the master film, and means for separating the films and rewinding them.

33. In a machine for printing films, reels 120

for holding a master film and a blank film, a dye tank, means to pass the master film through it, means to unite the films by surface contact and exclude air therebetween, and squeegee rollers to press the films together.

34. In a machine for printing films, means for extending the films to provide slack, a reciprocating mechanism having pawls which periodically occupy perforations in the master film to advance it, a film-holding block operated to hold the films down when advance has ceased, a reciprocating perforator mounted with relation to the pawls in such a manner as to perforate the printed film through the centers of the perforations in the master film, and means for separating the films and rewinding them.
35. The process of making from a perfo-

rated motion picture master film, a secondary motion picture film suitable for enlarged projection in a projecting machine of the intermittent type in which the individual pictures bear the same relations to the perforations as the pictures of the film from which it is obtained bear to its pictures, which comprises coloring the master film, placing the master film in contact with the secondary film until the coloring matter has been taken by the secondary film, perforating the secondary film to correspond to the perforations in the master film while the two are in contact, and separating the secondary film from the master film.

In testimony that I claim the foregoing, I have hereunto set my hand this 11th day of July, 1923.

ROBERT JOHN.
